HAIR DYE APPLICATOR

William Stern, New York, N. Y.

Application August 5, 1941, Serial No. 405,477

5 Claims. (Cl. 15—133)

This invention relates to applicators in general, and particularly to dispensing hair dye applicators.

Devices for dispensing liquids are well-known in the art. The present invention contemplates an applicator, whereby the flow of hair dye or any other liquid held in the dispenser may be accurately controlled through the manipulation and positioning of the device in respect to the scalp. Dyeing of hair requires careful handling, since hair dye has to be uniformly distributed over the scalp in order to prevent "streaks," which latter occur where hair dye is too generously applied, whereas other places are dyed insufficiently.

Broadly the device consists of a dye-containing supply vessel of a rather slim, elongated construction so that the vessel itself may be used as a handle. The end of the vessel is closed by the applicator head, which is so designed that when the vessel is tilted dye matter is supplied through a replaceable applicator element in the applicator head to the scalp, while when the vessel is held in a substantially horizontal position the dye is prevented from passing into the applicator element, while the latter is being used for rubbing in and distributing the already dispensed dye portion.

It is the object of this invention therefore, to provide a device whereby the dispensing of the liquid may be controlled by variously positioning the device.

Another object of this invention is to provide an applicator, comprising a dye-holding handle with a broadened closure or head, in which head is formed a substantially wedge-shaped recess for accommodating an applicator element, such as wick material or hair bearing cloth or fur, and wherein a supply passage for the dye is provided extending from the interior of the handle to the applicator element, and wherein the supply passage is so designed as to pass the dye or other liquid to the applicator element when the device is tilted, and to prevent discharge of liquid when the device is held in a substantially horizontal position.

A further object of this invention is to provide in a hair dye applicator a substantially rounded, relatively broad applicator head, the ends of which extend sidewise from its central portion which is attached to the handle, the latter forming a supply vessel, and wherein the head is provided with an air duct adapted to connect the interior of the vessel with the atmosphere, and a

supply passage controlled by the positioning of the device.

The foregoing and still further important objects and advantages of the present invention will become more fully apparent from the ensuing description, in connection with the accompanying drawing, which latter are intended to illustrate the principle of my invention, without limiting it to the actual showing, and in which—

10 Fig. 1 is a side elevation of an applicator, partially in section, in its tilted position, showing one embodiment of my invention;

Fig. 2 is an end view of the applicator head;

Fig. 3 is a partial cross section taken on line 15 3—3 of Fig. 1;

Fig. 4 is an end view seen from the right side of Fig. 1;

Fig. 5 is a detail view of an applicator spreader employed in my device;

20 Fig. 6 illustrates a modified form of an applicator element employed in my device; and

Fig. 7 is a partial cross section through another embodiment of my invention.

Referring now specifically to the figures, numeral 10 denotes an elongated, relatively slim-dimensioned vessel for accommodating a supply of hair dye 11. The vessel serves as handle for the device. The open end of the vessel is preferably threaded at 12 or is otherwise adapted for

30 accommodating the central portion 13 of applicator head 14. This head extends sidewise from closing portion 13, as clearly seen in Figs. 2, 3 and 4. In the body of head 14 there is arranged a substantially wedge-shaped recess 15, open at one 35 end and closed at the other (see Fig. 3). At the bottom of the recess there is provided a distributing channel 16, from the center of which extends a supply passage 17, which terminates as near as possible to the wall of vessel 10, as indicated at 18. An air duct or passage 19 extends from the top of the head into the interior of the vessel and also terminates as near as possible to the vessel wall at 20. Within recess 15

40 there is provided an applicator element 21, which is shown in Figs. 1, 2, 3 and 4 in the form of a wick. The wick material is bent upon itself, as indicated at 22, while its ends 23, extending into the interior of recess 15 and are spread against the inclined walls of the recess by a perforated 45 spreading device 24, shown in detail in Fig. 5. This spreading device is also of a wedge-shaped cross section, and is preferably provided with a handle end 25, by means of which it may be removed from or inserted into the recess. The opposite end 26 of the spreader is arrow-shaped in

50

order to facilitate its insertion. Channel 16 and the perforations in the spreader are designed to evenly distribute the liquid hair dye over the entire length of applicator element 21.

Due to the fact that the interior terminus of supply passage 17 is located as near as possible to the wall of vessel 10, the hair dye may enter the passage only when the vessel is tilted, as seen in Fig. 1. When the vessel is held horizontally no liquid will be passed to the applicator.

While I have found that wick material arranged in the manner indicated gives very excellent results, the same may be substituted by a hair bearing element such as shown at 21' in Fig. 6. A piece of fur bent upon itself in the manner indicated will serve the same purpose.

In the embodiment shown in Fig. 1, the attached portion of the head is provided with an internal thread and a central extension 27 projecting into the interior of the vessel. In Fig. 7 such extension is eliminated and the head 28 is somewhat narrower in design. Due to the elimination of extension 27, supply passage 17' is continued by means of tubing 29, and air duct 19' is similarly extended by tubing 30 towards the wall of vessel 10. Otherwise the arrangement and the operation of the device remains the same. In both embodiments illustrated the air and supply passages project into the vessel beyond the confine or body of the head proper.

The applicator head, the design and size of which may of course be changed to adapt the device for varying uses, is purposely designed for facilitating the application of dye over a relatively broad area, which feature is important from the standpoint of preventing streaking. When a sufficient quantity of dye is released through tilting the vessel in the manner shown in Fig. 1, it is important that for the duration of the next following operation, the spreading and rubbing in of the dye, no further dye material be dispensed. By either tilting the device downwards or by holding it horizontally, practically no dye material will pass to the applicator element.

In order to facilitate tilting of the device during the dyeing and dye distributing operations, the entire outer contour of the solid head body is rounded or cylindrical. The wedge-shaped recess for the reception of the applicator element is located along one side of and rearwards in respect to the front end of the head, as clearly seen in Figs. 1 and 7.

While specific forms of my invention are illustrated and described, be it understood that changes and improvements may be incorporated therein, without departing from the broad scope of my invention, expressed in the annexed claims.

I claim:

1. In a hair dye applicator, the combination with a relatively slim-bodied supply vessel, of a closure for the latter, comprising a solid-bodied, elongated head, adapted to extend substantially transversely in respect to the closed end of the vessel, said head having a rounded outer surface, an undercut recess provided along one side of the head lengthwise of its body, said recess being arranged rearwards in respect to the rounded front end of the head, a supply passage connect-

ing the interior of the vessel with the recess, an air passage in the head connecting the atmosphere with interior of the vessel, an applicator element in said recess and means for spreading and wedging the element against the walls of the recess for fastening it in the latter, said means having communicating and distributing passages adapted to pass liquid through the supply passage to the applicator element, the interior terminus of the supply passage being so arranged that when the vessel is held in a substantially horizontal position the terminus will extend above the liquid, whereas when the vessel is tilted upwards, liquid is permitted to pass to the applicator element.

2. In a hair dye applicator, as set forth in claim 1, said supply and said air passages extending into the vessel beyond the confine of the head body.

3. In a hair dye applicator, as set forth in claim 1, said applicator element comprising an absorbent member bent upon itself and extending with its bent portion beyond the recess, while one end of the spread portions of the applicator, in engagement with the walls of the recess, abuts with the closed end of the latter.

4. In a hair dye applicator, a vessel, a substantially cylindrical applicator head forming the closure for the vessel and extending substantially transversely in respect to the closed end of the vessel, a wedge-shaped recess provided in the head, but being remote from the rounded front side thereof, and having a longitudinal distributing channel, a supply passage extending from the channel through the head body into the interior and terminating near the wall of the vessel, an air duct connecting the atmosphere with the vessel interior and also terminating near the wall of the vessel, a folded applicator element removably associated with and extending with its folded portion from said recess, and a removable wedge-shaped, perforated spreader forcing the interior ends of the applicator element against the walls of the recess, the perforations of the spreader being adapted to pass liquid from the distributing channel to the spread interior portions of the applicator element.

5. In a hair dye applicator, an elongated applicator head adapted to be removably associated with and to close the end of a relatively slim vessel, the body of the head being rounded and extending transverse beyond the closing means for the vessel, a wedge-shaped recess arranged longitudinally in the rounded head portion, but remote from its rounded front side, a distributing channel at the bottom of the recess, an applicator element bent upon itself and removably secured in the channel, a removable, perforated, wedge-shaped spreader forcing the interior ends of the element against the walls of the recess, a supply passage extending from the channel into and towards the wall of the vessel, and an air duct directed from the upper head body into the vessel and against its wall, the perforations of the spreader being adapted to pass liquid to and distribute it over the spread interior ends of the applicator element.

WILLIAM STERN.
